UNITED STATES PATENT OFFICE.

ANTON HERZINGER, OF PLAINVIEW, NEBRASKA.

TANK-HEATER.

1,183,730.

Specification of Letters Patent. Patented May 16, 1916.

Application filed March 22, 1915. Serial No. 16,120.

To all whom it may concern:

Be it known that I, ANTON HERZINGER, a citizen of the United States, residing at Plainview, in the county of Pierce, State of Nebraska, have invented certain new and useful Improvements in Tank-Heaters; and I do hereby declare the following to be a full, clear, and exact description of the invention, such as will enable others skilled 10 in the art to which it appertains to make and use the same.

This invention relates to improvements in water heaters.

The principal object of the invention is to 15 provide a novel and efficient device for heating water so as to induce a proper circulation.

Another object is to provide a heating device disposed within a closed tank and 20 means for absorbing and revaporizing the condensation of moisture accumulating within the tank so that danger of the heating burner being put out is eliminated or reduced to a minimum.

25 Other objects and advantages will be apparent from the following description when taken in connection with the accompanying drawing.

In the drawing: Figure 1 is a top plan 30 view of the device, Fig. 2 is a vertical section therethrough, Fig. 3 is a horizontal section therethrough, and Fig. 4 is a perspective view of the moisture absorbing and dissipating means in connection with a portion of the burner.

Referring particularly to the accompanying drawing, 10 is a tank or other suitable inclosure which is provided with a hinged cover 11. Disposed in the bottom of the 40 tank is a gasoline or other suitable burner 12, the same being fed from a tank 13 mounted at one side and at the upper end of the tank. Suitably supported over the burner is a drum 13^a, the same being completely closed and having extending through 45 its top and bottom walls hot air flues 14. Leading into the lower portion of the drum are pipes 15 which conduct the cold water thereto while connected to the upper portion 50 at the side of the drum are pipes 16 which conduct from the drum the heated water as it rises.

Extending down into the tank at points adjacent the burner are pipes 17 which 55 conduct air to the burner.

In the bottom of the tank adjacent the burner is a member 18 formed of clay, cement or other fire-resisting but porous material. This member includes the base 19 and a laterally directed portion 20 at the 60 upper end, which is disposed over the flame of the burner. By reason of the fact that the tank is closed there will be a collection of condensed vapors therein which run to the bottom of the tank and, in time rise 65 to a point sufficient to extinguish the flame of the burner. By providing the member 18 of porous material the greater part of this condensation is quickly absorbed and then revaporized over the burner so that the 70 depth of the condensation in the bottom of the tank is kept down to a minimum and the flame of the burner protected therefrom.

What is claimed is:

75

1. In a water heating device, a receptacle, a burner mounted in the receptacle, a water containing drum mounted over the burner, means for conveying air to the burner, and means disposed adjacent the burner and 80 having a part extending thereover for absorbing condensation of moisture within the receptacle and delivering the same over the burner for revaporization.

2. In a water heater, the combination with 85 a tank and a burner and water drum mounted therein, a member formed of porous fire-proof material disposed in the bottom of the receptacle and having a portion extending laterally over the burner, the condensation or moisture which collects in the bottom of the receptacle being absorbed by the 90 said member and revaporized over the burner, whereby the burner is protected from extinguishing by the said collection of 95 moisture.

3. In a water heating device, a receptacle, a burner mounted in the receptacle, a water containing drum mounted over the burner, and means for absorbing condensation of 100 moisture within the receptacle and by a capillary attraction delivering the same over the burner for revaporization.

In testimony whereof, I affix my signature, in the presence of two witnesses.

ANTON HERZINGER.
